E. W. KIRBY

CONTAINER

Filed July 12, 1924

INVENTOR
E. W. Kirby
BY
H. M. S. & C. L. ATTORNEY

UNITED STATES PATENT OFFICE.

ELSIE W. KIRBY, OF NEW YORK, N. Y.

CONTAINER.

Application filed July 12, 1924. Serial No. 725,703.

To all whom it may concern:

Be it known that I, ELSIE W. KIRBY, a citizen of the United States, residing at New York city, county of New York, borough of Manhattan, and State of New York, have invented new and useful Improvements in Containers, of which the following is a full, clear, and exact specification.

My invention relates to containers and 10 refers particularly to containers suitable for use with powders.

While it is generally admitted that loose powders are preferable to so-called powder compacts for toilet use, the latter have received considerable popularity based upon 15 their convenience.

Among the disadvantages incident to the employment of loose powder are its liability to sift out of the container when being 20 carried, its sifting and dusting over the clothes of the user when being employed, the waste of powder due to loss and the unhygienic method employed in exposing the entire powder mass when being used.

25 On the other hand, the loose powder has many advantages over powder compacts in that it is in finer condition, is free from harsh and injurious binding materials, is more economical when properly used and 30 can be more readily applied to the necessary powder puff.

The device of my invention overcomes the objections incident to the employment of loose toilet powders whereby advantage may 35 be taken of their valuable properties.

In the device of my invention, the powder 40 mass is completely protected from accidental, or atmospheric, contamination, the escape of the powder from the container is impossible and an excessive removal of powder is prevented, an amount of powder only sufficient for the desired purpose being removed from the mass and this being automatically deposited upon a tray-like 45 portion of the device for puff employment.

These and other advantageous features of my device will be evident upon a consideration of my specification and its accompanying drawings.

50 In the accompanying drawings illustrating modified forms of the device of my invention, similar parts are designated by similar numerals.

Figure 1 is a perspective view of one form 55 of my device in open position for use.

Figure 2 is a central longitudinal section

of the device of Figure 1 in closed position, the broken lines indicating open position.

Figure 3 is a section through the line 60 3-3 of Figure 2.

Figure 4 is a perspective view of a powder carton suitable for use in the device.

Figure 5 is a broken top plan view of a modified form of a portion of my device. 65

The particular form of the device of my invention, shown in the accompanying drawings, comprises a tray-bottom member having the bottom 10 and the upwardly extended flange 11. The container bottom 70 thus formed has a transverse wall 12 with a plurality of openings 13, 13, 13 in the central portion thereof. The wall 12 carries the pivotally attached closure 14, capable of covering and closing the openings 75 13, 13, 13, the closure 14 having the bent portion 15 for ease of manipulation.

Hingedly attached to the bottom flange 11 at 16 is a cover, or lid, having the top member 17 and the extended flange 18, the 80 inner face of the top member 17 carrying the mirror 19. The top flange 18 carries the catch 20 coacting with the member 21 of the bottom flange 11 to maintain the device in closed position. 85

Hingedly attached at 16 is a compartment cover, or lid, 22 being maintained in normal closed position over one of the compartments in the bottom by means of the spring 23. The compartment cover 22 carries 90 a plurality of extended pins 24, 24.

One particular replaceable means for employing powder with my device, is shown in Figure 4, comprising an annular cardboard carton 25, one portion of the side of which 95 has been cut away and the opening covered with a piece of paper 26. The carton 25 is of such size that it will fit snugly into the bottom compartment covered by the lid 22. 100

The device is prepared for use as follows:

The paper 26 of the carton 25 is removed and the carton placed within the bottom compartment, with the openings of the carton caused by the removal of the paper 26 in alignment with the openings 13, 13 of the partition 12, the closure 14 being down and closing the openings 13, 13. The compartment cover 22 is then allowed to assume 105 its normal position over the carton, the pins 24, 24 entering the top cover of 110

the carton and preventing it from movement.

When it is desired to use the powder, the puff 27 is removed from the puff compartment, the closure 14 raised and the device slightly inclined in order that the requisite quantity of powder may pass through the openings 13, 13 into the puff compartment, when the openings 13, 13 are closed by the closure means 14, the puff 27 being employed to make use of the powder in the puff compartment.

It is evident that my device may be employed with loose powder not contained in a carton, in which case I prefer to have the transverse partition form an extended pocket 28, in order that all of the loose powder in the powder compartment may be rightly caused to pass through the openings 13, 13.

From the foregoing, it will be seen that my device is extremely compact, that it can be employed with replaceable powder cartons in the use of which the powder is doubly protected from sifting and contamination, that it is economical as there is no loss of powder, that it is cleanly as only sufficient powder may be placed upon the puff and that, therefore, it presents an efficient means for the carrying and use of toilet powders.

I do not limit myself to the particular size, shape, number, or arrangement, of parts as shown and described, as these are given simply as a means for clearly describing the devices of my invention.

What I claim is:—

1. In a powder container, in combination, a tray-bottom, a transverse wall within the bottom forming a plurality of compartments, the wall having openings therein, means for closing the wall openings, a cover for one compartment and a cover for the device.
2. In a powder container, in combination, a tray-bottom, a transverse wall within the bottom forming a plurality of compartments, the wall having openings therein, pivotal means for closing the wall openings,

a cover for one compartment and a cover for the device.

3. In a powder container, in combination, a tray-bottom, a transverse wall within the bottom forming a plurality of compartments, the wall having openings therein, pivotal means for closing the wall openings, a hinged cover for one compartment, means for normally maintaining the cover in closed position and a cover for the device.

4. In a powder container, in combination, a tray-bottom, a transverse wall with the bottom forming a plurality of compartments, the wall having openings therein, pivotal means for closing the wall openings, a hinged cover for one compartment, means capable of maintaining a carton within the compartment, means for normally maintaining the cover in closed position and a cover for the device.

5. In a powder container, in combination, a tray-bottom, a transverse wall within the bottom forming a plurality of compartments, the wall having openings therein, pivotal means for closing the wall openings, a hinged cover for one compartment, projecting members carried by the under face of the cover capable of insertion into a carton within the last mentioned compartment, means for normally maintaining the cover in closed position and a cover for the device.

6. In a powder container, in combination, a tray-bottom, a transverse wall within the bottom forming a plurality of compartments, the wall having openings therein, pivotal means for closing the wall openings, a hinged cover for one compartment, projecting members carried by the under face of the cover capable of insertion into a carton within the last mentioned compartment, spring means for normally maintaining the cover in closed position, a hinged cover for the device and a mirror carried upon the inner face of the device cover.

Signed at New York city, in the county of New York and State of New York, this 11th day of July, 1924.

ELsie W. KIRBY.
